UNITED STATES PATENT OFFICE.

JAMES E. BOYLE, OF BROOKLYN, NEW YORK.

WATER-CLOSET AND OTHER BOWLS AND PIPE-CONNECTION THEREFOR.

SPECIFICATION forming part of Letters Patent No. 291,140, dated January 1, 1884.

Application filed March 12, 1883. (No model.) Patented in England February 23, 1882, No. 882; in France February 23, 1882, No. 147,614; in Germany March 2, 1882, No. 20,286; in Belgium March 13, 1882, No. 57,349; in Austria-Hungary May 8, 1882, No. 8,083, and in Canada July 3, 1882, No. 31,219.

To all whom it may concern:

Be it known that I, JAMES E. BOYLE, a citizen of the United States, residing at Brooklyn, in the county of Kings and State of New York, have invented certain Improvements in Water-Closet and other Bowls and in Pipe-Connections Therefor, of which the following is a specification.

The principal object of this invention is to provide the earthenware bowls of water-closets or lavatories, or other bowls used in plumbing, with simple and effective means for connecting pipes to them in an air or water tight manner.

Another object is to effect certain improvements in the connections and setting of water-closet bowls.

Figure 1 of the accompanying drawings is a vertical mid-section of a water-closet bowl and traps constructed according to my invention. Fig. 2 is an elevation of the bowl and flushing-pipe alone, their connection being in section cut along the line 2 2 and looking in the direction of arrow 2 in Fig. 1. Fig. 3 is a longitudinal mid-section of the connection on a larger scale. Fig. 4 shows the parts forming the connection in elevation. Fig. 5 is a fragmentary transverse section of a portion of the bowl, showing a modified connection. Fig. 6 is a similar section to Fig. 1, showing the application of my connection to a double-trapped closet-bowl. Fig. 7 is a front elevation thereof. Fig. 8 is a fragmentary plan thereof, partly in section, and Fig. 9 is a rear elevation of a lavatory bowl or basin, showing my connection in section applied as the overflow-connection.

In my Patent No. 255,485, dated March 28, 1882, I have shown an earthenware water-closet bowl molded in one piece with two successive traps in the soil-passage.

Figs. 6 and 7 of the accompanying drawings show a bowl of the same general construction. This double-trapped bowl is designed to be used where there is no trap in the soil-pipe beneath the floor; but for situations where that trap exists, or where its use is preferred I have designed the closet-bowl shown in Fig. 1, where but one trap is made in connection with the bowl.

Referring to Figs. 1, 6 and 7, A is the bowl. B is the soil-passage leading therefrom. C is the trap in that passage, by which water is retained in the bowl. D is the second or lower trap. (Not shown in Fig. 1.) a is the outlet from the bowl; d, the air-space between the two traps; e, the suction-pipe leading from this air-space to the tank above, (not shown;) l, the flushing-pipe leading down from that tank to the bowl A, and k the flushing-rim of the bowl. These parts are all, except as herein-after specified, constructed substantially as set forth in my said patent, where they are designated by the same letters of reference here applied to them.

I will first describe the construction shown in Figs. 1 to 4. Only the bowl A is made of earthenware. The passage B and trap C are made of cast-iron by preference, because of its cheapness. This iron casting, lettered E, is formed at its connection with the bowl with a flat flange, b, on which the bowl rests. The latter is provided at its bottom with a flat flange, c.

Between the flanges c and b a rubber gasket or other elastic packing-ring, f, is placed, and the two flanges are pressed closely together by screw-clamps g, one of which is shown in Fig. 1. The flange b is cast with horizontally-perforated ears h at intervals, and through each of these a hooked bolt, i, is dropped from above, its upper hooked end being turned away from the bowl. After being thus inserted the hooked portion of the bolt is turned toward the bowl, so that it overhangs the flange c. A nut is then screwed onto the lower end of the bolt and tightened against the ear h, thereby drawing down the flange c and compressing the packing f. This form of clamp is cheap and strong and cannot slip off. The suction-pipe e is connected in any usual way to the casting E, the upper portion, E', of which is preferably cast in a separate piece and united by flanges.

I will now describe the connection between the flushing-pipe l and the bowl A, which forms the most important feature of my invention. The bowl A is molded with a cylindrical tubular provision, F, with open ends, which I shall call the "barrel," on its exterior and

near its top. As shown in Figs. 1 and 2, this barrel is arranged horizontally, and its interior communicates through a port or opening, *m*, with the interior of the flushing-rim *k*. The pipe *l* is connected to one end of this barrel, and the other end is closed. The connection is made by means of a tubular screw-clamp, the shank or tie of which passes through the barrel. A flanged tube or thimble, *G*, enters the barrel at one end, and a flanged cap, *H*, closes the other. The thimble *G* is preferably made to extend nearly through the barrel, and is cut away at *I*, so that its interior may communicate freely with the interior of the barrel. Tie portions or bars *J*, *J* are thus left, which extend nearly through the cavity of the barrel, and on their end is a tubular screw, *J'*, onto which the cap *H* screws. The thimble *G* is formed with a flange, *G'*, and a rubber ring or gasket, *n*, is slipped over the thimble against this flange, Fig. 4. The cap *H* has a flange, *H'*, against which is another gasket, *n*. The connection is put together by inserting the thimble *G* into the barrel *F* until its flange *G'* bears (through the gasket *n*) against the end of the barrel. The cap *H* is then placed against the opposite end of the barrel, its internally-threaded portion is engaged with the screw *J'*, and it is rotated to screw it up tightly thereon by means of any suitable wrench. The barrel *E* is thus embraced with considerable pressure between the flanges *G'*, *H'*, a tight joint being made by the intervention of the gaskets *n*, *n*. The pressure upon the barrel is in the direction of its axis, and as its walls are substantially straight from end to end this strain is resisted by them in a direct line, so that a very powerful pressure may be applied without danger of crushing the barrel. The portion *p* of the thimble *G* projecting beyond the flange *G'* is screw-threaded to engage a union-nut, *K*, by which a spud, *L*, is pressed against the end of the thimble, a tight joint being made by interposing a gasket, *q*. The lead pipe *l* is joined to this spud *L* by a wiped joint or in any other suitable manner. Whenever it becomes necessary to disconnect the pipe *l* from the bowl, the nut *k* may be unscrewed, thus separating the spud *L* from the thimble *G*.

Fig. 5 shows the barrel *F* formed upon the bowl *A*, with its axis vertical, instead of horizontal. In all other respects the construction is the same as already described.

Figs. 6, 7, and 8 show the bowl and traps all made in one piece of earthenware, with two barrels *F*, one communicating with the flushing-rim *k*, substantially as already described, the other arranged by its side and communicating with the air-space *d*. This latter barrel is lettered *F'*, and to it is connected the pipe *e*. The two thimbles *G*, *G*, Fig. 8, are inserted in the rear ends of the barrels *F*, *F'*, but do not project through them, and the caps *H*, *H*, which close their front ends, are screw-threaded. There are the

same flanges *G'*, *H'* and gaskets *n*, *n*. There is but one tie-bar, *J* to both barrels, and this passes between the barrels, instead of through them. A yoke, *N*, extends from one thimble, *G*, to the other, and bears against their flanges *G*, *G'*. Another yoke, *N'*, extends from one cap, *H*, to the other, and bears against their flanges *H'*, *H'*. The tie bar or bolt *J* connects the middles of these two yokes, and by screwing up the nuts *r*, *r* the yokes are drawn forcibly toward each other, thereby pressing the flanges *G'*, *H'* firmly against the ends of the barrels. 75

Fig. 9 shows my invention applied to a lavatory-bowl, for connecting the overflow-pipe therewith. The overflow-holes *m*, *m* open into the cavity of the barrel, which I have shown as arranged horizontally. The thimble *G* and cap *H* are the same as shown in Figs. 3 and 4, 85 except that the thimble has a branch, *L'*, projecting downwardly, to which the overflow-pipe *s* is connected. The union nut and spud are thus omitted.

Another feature of my invention (shown best in Figs. 1, 2, and 5) consists in forming a trap at the connection of the flushing-pipe *l* with the bowl. This is done in order that such foul gases as may accumulate in the flushing-chamber of the tank overhead may not descend through the flushing-pipe and enter the bowl, thereby vitiating the air of the room. To this end I make the lower side of the discharge end of the port *m* higher than the upper side of the opening through the thimble *G*, as shown in Figs. 1 and 2, so that in flushing the closet it is impossible for all the water which descends through the flushing-pipe to reach the bowl, the latter portion being retained in the cavity of the barrel and in the lower part of the flushing-pipe, as clearly shown. In Fig. 5 the same result is secured, the trap being by this construction sealed to a greater depth.

I claim as my invention—

110

1. A water-closet bowl or other earthenware bowl used in plumbing, provided on its exterior with a hollow tubular barrel molded in one piece with it, having opposite open ends, and with a port or opening through the side of the bowl, affording communication between the cavity of the barrel and the interior of the bowl, substantially as set forth.

115

2. An earthenware bowl provided with an open-ended cylindrical barrel on its exterior, and an opening extending from its interior to the cavity of said barrel, in combination with a thimble entering one end of said barrel, a cap closing the other end thereof, and a clamp for pressing said thimble and cap forcibly toward each other, thereby embracing the barrel between them, substantially as set forth.

120

3. The combination, with bowl *A*, provided with barrel *F*, of thimble *G*, having tie-bars *J*, *J*, screw *J'*, and screw-cap *H*, engaging said screw, substantially as set forth.

125

4. The combination, with bowl *A*, provided

with barrel F, of thimble G, having tie-bars J J, screw J', screw-cap H, union-nut K, and spud L, substantially as set forth.

5. A water-closet bowl formed with a tubular barrel for connecting with the flushing pipe, and provided with a trap or water-seal at the connection between the pipe and the bowl, whereby the air in the pipe is normally isolated from the bowl, substantially as set forth.

In witness whereof I have hereunto signed my name in the presence of two subscribing witnesses.

JAMES E. BOYLE.
